COMBINED TOBACCO POUCH AND
CIGARETTE ROLLING DEVICEMichael J. Kehoe, Springfield, Ohio, assignor of
forty-nine per cent to Fred J. Topp, Spring-
field, Ohio

Application December 20, 1944, Serial No. 568,950

5 Claims. (Cl. 131—73)

1

This invention relates to a combined tobacco pouch and cigarette rolling device.

One of the objects of the invention is to provide a new and improved type of cigarette rolling device which is combined with a tobacco pouch.

Another object of the invention is to provide a cigarette rolling device of the type described which is detachably associated with a tobacco pouch.

A further object of the invention is to provide a simple device by means of which the ordinary user can roll a cigarette and pack it with tobacco without spilling the tobacco.

Another object of the invention is to provide a device of the type described suitable for making round, firmly packed cigarettes from loose tobacco.

Other objects and advantages of the invention will be apparent by reference to the following description in conjunction with the accompanying drawings, in which,

Figure 1 is an elevational view of a combined tobacco pouch and cigarette rolling device, as provided in accordance with this invention, the element shown in Figure 4 being removed therefrom;

Figure 2 is a cross-sectional view of the device illustrated in Figure 1 with the element of Figure 4 in place;

Figure 3 is a cross-sectional view of the device taken centrally and at right angles to the view shown in Figure 2;

Figure 4 is a cross-sectional view of the mandrel or forming element on which the cigarette paper is rolled into a tube, as more fully described hereinafter;

Figure 5 is a perspective view of the beginning of the rolling operation by which a cigarette paper is rolled onto the mandrel illustrated in Figure 4;

Figure 6 is a perspective view illustrating the mandrel of Figure 4 with the cigarette paper rolled therearound;

Figure 7 illustrates the manner in which the mandrel containing the rolled cigarette paper is inserted into the tubular member associated with the tobacco pouch;

Figure 8 illustrates the position of the rolled cigarette paper in the tubular packing member associated with the tobacco pouch after the mandrel shown in Figure 7 has been withdrawn;

Figure 9 illustrates the manner in which the tobacco is packed into the tubular rolled cigarette paper;

Figure 10 is a cross-sectional view somewhat similar to Figure 3, but showing a modified form of the invention.

Referring to Figure 1, the device illustrated

2

therein comprises a pouch 1 made of cloth, or other suitable material, and provided with a recessed or indented portion 2 around which is tied a drawstring 3, or other suitable element adapted to constrict the upper end of the pouch at the recessed portion 2.

By loosening the drawstring 3 tobacco can be introduced into the pouch through the top 4. The upper side walls 5 of the tobacco holding portion of the pouch are preferably tapered, as shown, in order to cause the tobacco to be funnelled in the direction of the neck or recessed portion 2 when the pouch is inverted.

Within the pouch is a cigarette rolling device 6 generally indicated by the numeral 6 and illustrated by dotted lines in Figure 1. As illustrated in Figure 2, the cigarette rolling device 6 comprises a mandrel or forming member 7 within a hollow tubular member 8, which is provided at

its lower end with a funnel-shaped opening 9. The elements 7 and 8 may be formed of plastic or other suitable material. The mandrel 7 preferably has a slit or opening 10 extending longitudinally on one side thereof, as shown in Figure 4, in order to provide resiliency, although it will be understood that the material from which the mandrel is made, as well as the material from which the tubular member 8 is made, may also be somewhat resilient. The mandrel 7 is closed at the top 11 in order to prevent the escape of tobacco in case the tobacco pouch 1 should be turned upside down when not in use. The outer surface of the mandrel 7 is preferably smooth. On the other hand, the upper part 12 of the inner surface of the tubular member 8 is preferably roughened, as shown in Figure 2.

A packing member of plunger 13 is fastened on the inside and to the central part of the bottom of the pouch 1 in any suitable manner, for example, by means of a nail or a screw 14 extending through the pouch 1 from the outside in the manner illustrated in Figure 2. The packing member or plunger 13 may be tubular, if desired, but is preferably closed at its upper end and is also closed at its lower end 16 due to the fact that it is pressed against the bottom of the pouch 1 and held in that position by the fastening means 14.

It will be observed that the tamping member 15 or plunger 13 preferably has its upper edge 15 slightly above the recessed portion 2 of the pouch 1. The assembled cigarette rolling device, including the mandrel 7 and the tubular member 8, is positioned over the packing member 13 in the manner illustrated in Figures 1, 2 and 3, and

the assembly is preferably of sufficient length that both of the elements 7 and 8 will project beyond the recessed portion 2 and can be grasped by the finger.

In order to maintain the shape of the pouch and to assist in positioning the elements 7 and 8, means are provided to maintain the recessed portion 2 in a relatively fixed position vertically with respect to the bottom of the pouch 1. In Figure 2 the means in question comprises a string, cord, thread, or the like, 17 which is sewed or otherwise fastened at one end 18 to the pouch 1 near the recessed portion 2 and extends downwardly to the bottom of the pouch where it is also sewed or fastened at point 19, thence upwardly again to the opposite side of the pouch where it is sewed or fastened at point 20. This serves to limit the vertical movement of the pouch with respect to the plunger or packing member 13 and also serves to control the position of the plunger 13 with respect to the elements 7 and 8. The cord 17 also serves as an agitator for the tobacco and assists in funnelling tobacco of proper particle size toward the tubular element 8.

As shown in Figures 1 and 3, it is preferable to secure or join the opposite sides of the pouch 1 near the bottom thereof in the central areas 21 and 22 (Figure 1) so that the material of the pouch 1 closely surrounds the plunger 13 (Figure 3) while at the same time the areas 21 and 22 provide means whereby the bottom of the bag can be readily gripped between the fingers. As will be understood, the areas 21 and 22 may be formed by gluing together opposite sides of the bag or by sewing the bag in those regions, or in any other suitable manner. This represents a preferred feature of the invention. When the areas 21 and 22 are formed in the bottom of the bag in this manner, the central portion of the bag bulges upwardly and outwardly to form the areas 23 and 24 and tends to direct the tobacco toward the funnel-shaped end 9 of the tubular member 8.

The combined tobacco pouch and cigarette rolling device is ordinarily carried by the user in the form illustrated in Figure 2, or with the mandrel of Figure 4 inserted into the top of the tubular member 8 of Figure 1. The use of the device is illustrative by Figures 5 to 9 and may be described briefly as follows.

When it is desired to roll a cigarette the mandrel 7 is removed from the tubular member 8 and a cigarette paper P is moistened along one edge and rolled around the mandrel in the manner illustrated in Figure 5. The moistened portion of the cigarette paper preferably contains a remoistening adhesive.

The rolled cigarette paper in combination with the mandrel 7 then appears as in Figure 6 and is inserted into the upper end of the tubular member 8 in the manner shown in Figure 7 until the cigarette paper is wholly within the tubular member 8.

The mandrel 7 is then withdrawn, the withdrawal being facilitated by the roughened inner surface 12 of the tubular member 8 and the smooth outer surface of the mandrel 7. The mandrel 7 also preferably is formed of plastic material and is somewhat resilient by reason of the longitudinal slit or opening 10 so that it can be withdrawn readily without causing the withdrawal of the cigarette paper, thereby leaving the cigarette paper P within the tubular member 8 in approximately the position shown in Figure 8.

The pouch is then inverted in the manner

shown in Figure 9 and the user places his finger over the end 25, as illustrated in Figure 9, in order to keep the tobacco from falling out of the pouch through the tubular member 8. While the finger of one hand is being held over the end of tubular member 8, the fingers of the other hand can be used to move the plunger 13 up and down by grasping it in the areas 21 and 22, and thereby tamp or pack tobacco into the cigarette paper P. The entrance of the tobacco into the cigarette paper is facilitated by the funnel-shaped portion 9 of the tubular member 8 and also by the action of the plunger 13. The tamping member or plunger 13 is substantially flexible so that it will slide along the cigarette paper without crumpling it, but at the same time is sufficiently rigid so that it can be used to eject the completed cigarette.

The device is preferably so adjusted that there is a small space in the end 26 of the cigarette, which is not filled in order to prevent loose tobacco from being taken into the mouth of the user. This is accomplished by providing an arrangement of the various elements such that the plunger 13 has its upper end 15 extending slightly into the tubular cigarette paper P, when the pouch is fully extended and the funnel portion 9 of the element 8 is also in its fully extended position from the bottom of the pouch, as shown in Figure 8. When the tobacco is packed firmly up the end 15 of plunger 13 the finger may be removed from point 25 and the plunger 13 will push the completed cigarette out of the tube 8.

In the modified form of the device shown in Figure 10, the limiting means 17' is fastened around the neck of the tube 8 just above the funnel portion 9 at point 27 so that the tube 8 is always held in association with the pouch even when the latter is being filled with tobacco. Otherwise the construction is similar to that described with respect to Figure 2.

The invention is subject to some variation and modification. For example, the mandrel member illustrated in Figure 4 may be carried separately rather than as a component part of the combined pouch and rolling device, in which event the tubular member 8 would be closed by a cork or other suitable means to prevent the escape of tobacco. Other variations will be apparent to those skilled in the art.

The invention provides a compact device for carrying tobacco and for rolling cigarettes without spilling the tobacco. The construction of the device is simple and inexpensive. There are few component parts and their arrangement and operation are simple and readily understood by the average user.

Having thus described the invention, what I claim as new and desire to secure by Letters Patent of the United States is:

1. A combined tobacco container and cigarette rolling device comprising a container for holding loose tobacco, said container being provided with an opening, a tubular member extending from the inside of said container through said opening adapted to hold a tubular rolled cigarette paper against its inner wall, and a plunger held by said container and extending into said tubular member, the plunger being fastened to the bottom of the pouch and the sides of the pouch adjacent to the lower edge of the plunger being secured together to form flattened areas readily grasped between the fingers to permit movement of the plunger longitudinally with respect to the tubular member, said plunger being adapted for

movement longitudinally of said tubular member to pack tobacco within said rolled cigarette paper positioned against the inner wall of said tubular member.

2. A combined tobacco pouch and cigarette rolling device comprising a pouch for holding loose tobacco, said pouch being provided with a restricted opening, a tubular member extending from the inside of said pouch through said opening, a plunger fastened to the bottom of said pouch and extending into said tubular member, said plunger being adapted for movement longitudinally of said tubular member to pack tobacco within a rolled cigarette paper positioned against the inner wall of said tubular member, and limiting means flexibly connecting the bottom of said pouch to a portion of said pouch adjacent the inner opening of said tubular member to limit the longitudinal movement of said plunger and said pouch with respect to said tubular member.

3. A device as claimed in claim 2 in which said limiting means comprises a cord fastened to the bottom of said pouch adjacent the end of said plunger and extending on opposite sides of said plunger to the side of said pouch adjacent said restricted opening and being fastened to said pouch adjacent said restricted opening.

4. A device as claimed in claim 2 in which said limiting means comprises a cord fastened to the bottom of said pouch adjacent one end of said plunger and fastened around the lower end of said tubular member.

5. In a cigarette rolling device, the combination of a tubular member and a mandrel adapted to fit within said tubular member, the outer surface of said mandrel being smooth to permit its withdrawal after a cigarette paper has been wound therearound and inserted into said tubular member and at least a portion of the inner surface of said tubular member being provided with means to increase the frictional resistance against the outside of the rolled cigarette paper when said mandrel is withdrawn.
